UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed October 15, 1923. Serial No. 312,722.

This invention relates to mining machines and more particularly, but not exclusively, to coal mining machines of the continuous cutter, flexibly fed type.

5 An object of this invention is to provide an improved coal mining machine of the continuous cutter, room and pillar, low vein type having improved flexible feeding means whereby the machine may be fed and controlled in an improved manner. Another object is to provide an improved room and pillar coal mining machine of an extremely low and compact character especially adapted to use in low vein work. Still another object of 10 this invention is to provide an improved room and pillar coal mining machine having improved cutting and feeding mechanisms respectively driven from opposite ends of the driving motor, thereby rendering the machine exceedingly low and compact. Another object of 15 this invention is to provide an improved feeding mechanism for a coal mining machine comprising simultaneously or independently operable feed operating and controlling members respectively adapted to cooperate with flexible feeding and controlling elements. Yet another object is to provide an improved mining machine having simultaneously or independently operable feed 20 controlling members and improved clutch mechanism for controlling the same. A further object is to provide an improved mining machine having an improved compact general arrangement of parts.

25 With these and other objects in view this invention resides in the novel features of construction, formation, combination, and arrangement of parts to be hereinafter more fully described, claimed, and illustrated in 30 the accompanying drawings in which one embodiment of the invention is disclosed.

In these drawings,—

Fig. 1 is a top plan view of the improved mining machine.

45 Fig. 2 is a rear end elevational view of the machine shown in Fig. 1.

Fig. 3 is a transverse horizontal sectional view illustrating details of the machine feeding mechanism, parts being shown in top plan.

Fig. 4 is a transverse vertical sectional view taken substantially on line 4—4 of Fig. 3.

Fig. 5 is a detail sectional view taken on line 5—5 of Fig. 3.

Fig. 6 is a central longitudinal vertical sectional view taken substantially on line 6—6 of Fig. 1 and illustrating details of the cutting mechanism.

Fig. 7 is a central longitudinal vertical 60 sectional view taken on line 7—7 of Fig. 1 and illustrating details of the improved machine feeding mechanism.

Fig. 8 is a transverse vertical sectional view, partially in elevation, taken substantially on line 8—8 of Fig. 3.

Fig. 9 is a horizontal sectional view taken substantially on line 9—9 of Fig. 7.

Fig. 10 is a detail section taken on line 10—10 of Fig. 9.

Fig. 11 is a horizontal section taken substantially on line 11—11 of Fig. 7 and illustrating details of the improved drum control mechanism.

Fig. 12 is a fragmentary sectional view 75 taken on a plane corresponding to Fig. 11 and illustrating parts in a different position.

Fig. 13 is a similar view illustrating the parts in still another position.

Fig. 14 is a detail sectional view taken on line 14—14 of Fig. 13.

Fig. 15 is a sectional view similar to Figs 80 12 and 13 illustrating the parts in still another position.

Fig. 16 is a detail sectional view taken on line 16—16 of Fig. 15.

In this illustrative embodiment of the invention there is shown a mining machine designated as an entirety by the reference character 1 and which is herein of the same general type as that described and claimed in my copending application Ser. No. 179,357, filed March 29, 1927, now matured into Patent No. 1,815,873, patented July 21, 1931, the main feature of this invention residing in an improvement in the feeding mechanism. The mining machine is herein of the flexibly fed, continuous cutter type adapted to cut in accordance with the room and pillar system of mining and is of an exceedingly low

and compact character especially adapted to use in low vein work. The improved mining machine 1 comprises a machine frame 2 having a bottom plane surface 3 upon which the machine is slidably supported on the mine bottom during operation of the machine. Projecting longitudinally from and rigidly fixed to the forward end of the machine frame 2 is an elongated plane horizontal cutter bar 4 about the outer edges of which a cutter bit carrying cutter chain 5 is adapted to be orbitally circulated. Feeding of the machine may be accomplished by a pair of flexible feeding and controlling elements 6 and 7 herein cables or ropes, the feed cable 6 being wound upon a feed operating member or drum 8 while the controlling cable 7 is wound upon a controlling member or drum 9. The feed and controlling drums 8 and 9 are coaxially arranged in a superimposed relation on a vertical axis at the rear end of the machine, i. e., the end of the machine remote from the cutter bar. Referring more particularly to the machine it will be noted that the same herein comprises three sections, i. e., a motor section 10, a feed section 11, and a cutter carrying section 12, the feed and cutter sections being herein disposed at opposite ends of the motor section and rigidly connected to the latter in such manner as to form a rigid and very low, compact frame 13 slidably on the mine bottom.

In specifically describing the improved cutting mechanism it will herein be noted that housed within the motor section 10 is a driving motor, herein preferably of the electric reversible type, having its armature shaft 13 horizontally disposed and extending longitudinally of the machine. Suitably fixed to the forward end of this armature shaft, as shown in Fig. 6, is a bevel pinion 14 which meshes with a bevel gear 15 herein formed integral with a vertical shaft 16. This shaft 16 is suitably journaled in ball bearings 17 and has also formed integral therewith a spur pinion 18 meshing with a larger spur gear 19. The spur gear 19 has a depending hub portion 20 journaled on ball bearings 21 surrounding and supported by a vertical stud 22. As shown, the stud 22 is threadedly connected at its opposite ends as at 23 to detachable cap members 24 and 25 respectively suitably bolted to the machine frame. The depending sleeve portion 20 of the gear 19 is connected by a semi-permanent clutch 26 to a clutch member 27 having external clutch teeth 28 and a hub portion 29 surrounding the stud 22. Rotatably mounted on this hub 29 is a similar clutch member 30 connected as by a semi-permanent clutch 31 to the hub of a cutter chain drive sprocket 32. This cutter chain drive sprocket 32 is rotatably mounted on ball bearings 33 surrounding and supported by the vertical stud 22. The hub 29 of the clutch member 28 is

interposed between the lower bearing 21 for the gear 19 and the upper bearing 33 for the sprocket 32. The bearings 33 and the sprocket 32 are maintained in operative relation by means of a cup-shaped member or step bearing 34 in turn held in position by a detachable bottom plate 35. The frame section 12 is provided with a depending cylindrical portion 36 having formed therein a bore 37 within which is vertically reciprocable a cylindrical clutch shipper member 38 connected to a clutch member 39 having internal clutch teeth adapted to cooperate with the teeth on the clutch members 27 and 30. As shown in Fig. 6 the clutch shipper member 38 is adapted to be shifted axially by means of a lever 40 pivotally mounted at 41 in a suitable manner within the machine frame and connected at 42 to the clutch shipper member. The other end of this lever is pivotally connected at 43 to a link 44 in turn pivotally connected at 45 to an arm 46. This arm is suitably fixed to a horizontal shaft 47 extending transversely of the machine and having secured thereto at its opposite ends suitable control handles 48 (see Fig. 1). As illustrated the cutter bar 4 has formed thereon an upstanding annular portion 49 mounted on the depending portion 36 of the machine frame and rigidly fixed to the frame by screws 50. The lower portion of the cutter bar has an annular bottom support 51 surrounding and supported by the step-plate 34. It will be evident that when the clutch member 39 is in the position shown in Fig. 6 the clutch members 27 and 30 are connected and as a result the cutter chain driving sprocket 32 is connected in driving relation with the motor. The cutter chain drive sprocket may be disconnected from the motor by simply shifting the member 38 upwardly thereby disconnecting the clutch teeth on the member 39 from the teeth on the clutch member 30.

As shown in the drawings, the improved machine feeding mechanism specifically comprises a spur pinion 55 fixed to the rear end of the armature shaft 13. This motor pinion 55 meshes with a spur idler gear 56 (see Fig. 3) journaled on ball bearings 57 supported by a horizontal stud 58 suitably fixed within the feed frame section 11. This idler gear 56 in turn meshes with a spur gear 59 keyed at 60 to a horizontal shaft 61 rotatably mounted in ball bearings 62 suitably supported within the feed frame section. The shaft 61 has herein formed integral therewith a bevel pinion 63 meshing with a bevel gear 64 keyed at 65 to a horizontal shaft 66 extending transversely of the machine. The shaft 66 has secured thereto at its inner end by a key 67 a spur gear 68, the hub of the latter being internally bored to receive a ball bearing 69. This ball bearing is supported by a projecting stud or dowel 70 secured by screws 71 to the frame

section. It will also be observed that the bevel gear 64 is likewise internally bored at 72 to receive a ball bearing 73 likewise supported by a projecting stud or dowel 74 secured to the side of the feed frame section. Referring more particularly to Fig. 4 it will be noted that the spur gear 68 meshes with a spur gear 75 keyed at 76 to a horizontal shaft 77 arranged parallel with and above the shaft 66. The gears 68, 75 are change speed gears and it is obvious that these gears may readily be removed from their respective shafts and replaced by gears of different tooth ratio to obtain different predetermined feeding speeds to suit different mining conditions. As shown, the inner end of the shaft 77 is journaled through a ball bearing 78 carried within a bore formed within the hub of the spur gear 75. The ball bearing 78 is supported by a stud or dowel 79 similar to the stud 70. The opposite end of the shaft 77 is journaled in a ball bearing 80 suitably carried within a detachable bearing bracket 81 in turn supported on a dowel pin or stud 82 similar to the stud 74. It will be observed that the shafts 66 and 77 have respectively rigidly secured thereto intermediate their ends worms 83 and 84, the former having teeth inclined in the same direction but of steeper lead than the latter. The worms 83, 84 rotate relative to each other in opposite directions and respectively mesh with coaxially arranged worm gears 85 and 86 disposed on a vertical axis (see Fig. 8). These worm gears each have hub portions respectively journaled on ball bearings 87 and 88 suitably carried by the machine frame. These hub portions each carry spaced alined ball bearings 89 and 90 within which a vertically disposed shaft 91 is journaled. This shaft 91 has herein preferably formed integral therewith intermediate its ends an elongated spur pinion 92 which meshes with a large spur gear 93 keyed at 94 to a hollow vertical shaft 95, which is herein the main feed shaft. The shaft 95 is disposed at the longitudinal center of the machine and journaled at its upper end in a ball bearing 96 positioned by a detachable plate 97 and its lower end in a ball bearing 98 suitably mounted within the machine frame.

The mechanism for alternatively frictionally connecting the fast and slow speed worm gears 85, 86 to the shaft 91 to effect rotation of the drums 8 and 9 at different speeds in opposite directions comprises a pivoted shipper yoke 99 (see Figs. 3 and 8) carrying at its inner end suitable rollers 100 journaled on pins 101 carried by the arms of the yoke. These rollers are adapted to engage the plane surfaces of axially movable cylindrical clutch applying members or pressure plates 102 and 103, each having internal teeth 104 interlocked with the teeth of the pinion 92. The pressure plate 102 may load a series of clutch discs 105 carried by a member 106 connected to the plate 102 and held in position within the gear 85 by means of a split ring 107. The clutch plates 105 are interleaved with a series of clutch plates 108 carried by the gear 85. The pressure plate 103 may load a series of clutch discs 109 carried by a member 110, similar to the member 106, connected to the plate 103 and similarly held in its gear by a split ring 111. The clutch discs 109 are interleaved with a series of clutch discs 112 carried by the gear 86. The split rings 107, 111 are seated within annular grooves 113 formed in their respective gears and parts 106, 110 have flanges 114 engaging their cooperating rings. In accordance with the illustrative form of the invention the outer end of the shipper yoke 99 is provided with a bifurcated portion 115, the arms of which carry pins 116 on which rollers 117 are mounted. These rollers engage at their tops and bottoms washers 118 guided on bolts 119 (see Fig. 5) threadedly connected at 120 to an abutment member 121 rigidly secured at 122 to the side of the feed frame section. Interposed between the washers 119 and similar washers 122^a and encircling the side bolts 118 are coiled springs 123, the washers 122^a engaging adjustable abutment members 124 and 125 respectively threadedly connected at 126 within the frame section. It will thus be evident that the washers 118 and coil springs 123 together with their cooperating elements form a yieldable pivotal mounting for the shipper yoke 99, the coil springs being adapted to yield upon overload of either of the controlling clutches. The shipper yoke 99 is adapted to swing about its pivot by means comprising a crank pin or eccentric 127 formed integral with a rotatable rod 128 journaled at its opposite ends within roller bearings 129 suitably carried by the frame section 11. Secured to the outer end of the rod 128 is an operating handle 130 conveniently located at the rear end of the machine. Rotation of this rod 128 is limited by a pin and slot connection 131. It will accordingly be evident that rotation of the handle 130 effects rotation of the eccentric 127 and consequently the shipper yoke 99 is swung about its pivot and one or the other of the controlling clutches within the worm gears 85, 86 is applied thereby causing rotation of the shaft 91 at either a fast speed in one direction or at a slow speed in the opposite direction. The crank pin or eccentric 127 locks the shipper yoke in either its raised or lowered position when the center of the eccentric passes the vertical center of the rod 128.

The improved mechanism for effecting drum rotation and for simultaneously or independently connecting the drums in driving relation with the motor will now be described. Referring more particularly to Figs. 7 and 8 it will be observed that the main

feed shaft 95 has formed integral therewith at its lower end a spur pinion 135 meshing with an internal gear 136 disposed within and arranged coaxially with the upper feed drum 8. As shown in Fig. 7 this internal gear 136 is provided with a depending cylindrical flange having an inwardly projecting flanged portion 137 secured by screws 138 to a main bearing bracket 139. This bearing bracket 139 has its hub 140 journaled in a ball bearing 141 supported within a bracket 142. This latter bracket 142 has an upstanding cylindrical flange which fits a bore formed within the machine frame, this flange forming a cup-shaped recess which is adapted to receive lubricant for lubricating the bearings. The lower end of the bracket 139 is journaled on a ball bearing 143 supported by a detachable bottom plate 144. It will thus be seen that the internal gear 136 and bearing bracket 139 rotate together. As illustrated, extending axially through the hub 140 of the bracket 139 is a vertical stud 145 threadedly connected at 146 within the feed frame section. Threaded on the lower end of the stud is a nut 147 which when tightened is adapted to maintain the bracket 142, the bottom plate 144, and the parts supported thereby in assembled relation. The lower controlling drum 9 is supported on the radial flange 149 of a bearing sleeve 150 journaled on ball bearings 151 supported by a sleeve 152 carried by the main bearing bracket 139, this bearing bracket having an outwardly projecting flange 153 which underlies the flange on the sleeve 152 to thereby support the latter. The upper feed drum 8 is rotatably mounted on ball bearings 154 supported by the lower drum 9. Interposed between the adjacent surfaces of the drum flanges is a packing ring 155 which prevents entry of foreign matter through the space between the drums to the ball bearings. Similar packings are provided between the bottom flange of the lower drum and the frame, and between the bracket 139 and the bottom plate, and these packings likewise prevent entry of dirt or other foreign substance to the moving parts. In this improved construction a rotatable control cam or control member 156 is journaled on a bearing sleeve 157 supported by the hub of the rotatable bracket 139. This member 156 has formed thereon a plurality of upper cam surfaces 158, herein four, which are adapted to engage a plurality of driving discs or plungers 159 slidably mounted within radial slots 161 formed in the depending flange of the internal gear 136. Disposed below and offset from the cam surfaces 158 on the control member is a second series of cam surfaces 162 which are adapted to engage a plurality of driving discs or plungers 163 disposed below and engaging and supporting the discs 159. These discs 163 are likewise

slidably mounted within the slots 161 formed in the flange of the internal gear. Formed on the periphery of the control member 156 and disposed between the cam surfaces 158 and 162 thereon are a plurality of recesses 164 adapted to receive the discs 159 and 163 in certain positions of the control member. These plungers 159 and 163 are adapted to be slid into engagement with recesses 165 and 166 respectively formed on the inner periphery of the drums 8 and 9 as will later be described. The mechanism for effecting rotation of the control cam 156 to cause actuation of the plungers 159 and 163 comprises a spur gear 167 arranged in axial alignment with the drum axes and meshing with a spur gear 168 journaled on ball bearings 169. These ball bearings are supported on a stud 170 carried by a radially extending horizontal arm 171 herein formed integral with the stationary bracket 142. Meshing with this spur gear 168 is a spur pinion 173 preferably formed integral with a rotatable control shaft 174 extending axially through the hollow shaft 95. As shown in Fig. 7 the upper end of the control shaft 174 is slotted at 175 and arranged in this slot and pivotally mounted at 176 on the shaft is an operating and locking lever 177. Surrounding the upper end of the shaft 174 is a cup-shaped stop member 178 for the lever 177 having slots through which the arms of the lever project. An annular locking ring 179 is clutched at 180 to the shaft 95 and is held in position by a flanged nut 181 threadedly connected to the shaft 95. As shown in Fig. 1 this locking ring has a series of locking recesses or notches 182 formed therein with which the locking portion 183 of the lever 177 selectively cooperates. Stop members or abutments 183^a project upwardly from the ring 179 and these stops limit movement of the lever 177 so that the latter can turn only between the stops. Mounted within the upper end of the shaft 174 is a spring pressed plunger 184 which is engageable with a recess or notch 185 formed on the lever and this plunger maintains the lever in its operative locking position. From the foregoing it will be evident that the control cam 156 may be rotated to so actuate the plungers 159, 163 to simultaneously or independently connect the drums 8 and 9 to the internal gear 136 and as a result the drums may be driven together or separately at will. When the operator grasps the lever 177 releasing its engagement with the locking ring the control member 156 may be rotated. When it is desired to connect the upper drum 8 to the motor, it being understood that both drums are released from the driving gear 136, the operator rotates the shaft 174 and thereby rotates the control member 156 through the gearing 173, 168, 167 to the position shown in Figs. 7 and 11.

When the control member is rotated into this position the upper cam surfaces 158 engage the upper plungers 159 moving them from the position shown in Fig. 16 to the position shown in Fig. 7 thereby locking the upper feed drum 8 directly to the driving gear 136. When the parts are in this position the plungers 163 are released from the lower drum 9 and disposed within certain of the recesses 164 formed in the control member 156. If it is desired to effect drive of both drums the control member 156 is rotated still further counter-clockwise from the position shown in Fig. 11 thereby causing the lower cam surfaces 162 to force the lower plungers 163 from the recesses 164 in the control member into the recesses 166 formed in the lower drum 9 thereby locking this drum directly to the driving gear 136. It is therefore evident that both drums 8 and 9 may be positively locked to the driving gear 136 for rotation therewith. At certain times during feeding of the machine it is desirable to release the upper feed drum 8 from the motor while rotation of the lower control drum 9 continues and this is accomplished by rotating the control member into the position shown in Fig. 12 with the upper driving plungers 159 disposed within certain of the recesses 164 in the control member while the lower plungers 163 are held within the recesses 166 in the lower drum 9 by the cam surfaces 162, the upper plungers being released from the recesses 165 in the upper feed drum at that time. It will also be evident that upon suitable actuation of the friction clutches within the fast and slow speed worm gears 85 and 86 the drums 8 and 9 may be driven simultaneously or independently at a fast speed in one direction and at a slow speed in the opposite direction as will later be described.

As shown in Figs. 1 and 2 suitable guide sheaves or rolls 190 and 191 are provided at opposite sides of the forward end of the machine and these guide sheaves are mounted on swing arms 192 detachably connected by screws 193 to the sides of the frame section 12. It will also be noted that mounted at the left hand side of the upper feed drum 8 at the rear end of the machine as viewed in Fig. 2 is a guide sheave or roll 194 suitably journaled on the machine frame for guiding the feed cable 6. Disposed at the opposite side of the machine is a double guide roll or sheave 195 adapted to guide the cables extending from both drums. Disposed below the guide sheave 194 is a non-rotatable guide 196 having a lateral projection 197 for preventing the cable on the upper drum from dropping downwardly onto the lower drum. These guides 190, 191, 194, 195, 196 are adapted to guide the cables 6 and 7 during the various operations of the machine as will later be described. Moreover it will be noted that the motor housed within the frame sec-

tion 10 is adapted to be controlled by any suitable electrical controlling apparatus including a controller handle 198 conveniently located adjacent the clutch controlling handle 130.

The operation of the improved mining machine is as follows: Let it be assumed that the machine is positioned adjacent the coal face at the right hand rib and is about to make a sumping cut beneath the face. When the machine is so positioned the feed cable 6 is extended from the upper feed drum 8 rearwardly around the guide sheave 194 and then forwardly longitudinally of the machine around the front guide sheave 190 to a suitable anchor or roof jack disposed adjacent the coal face. The controlling cable 7 is extended from the lower controlling drum 9 rearwardly around the guide roll 195 and then laterally of the machine to a suitable anchor or roof jack adjacent the right hand rib. The operator then grasps the controller handle 198 and starts the motor. The control handle 48 is then manipulated moving the clutch member 39 to the position shown in Fig. 6 thereby connecting the cutter chain driving sprocket 32 to the motor and as a result the cutter chain 5 is rapidly circulated about the outer edges of the cutter bar 4. The operator then grasps the control lever 174 and rotates the control member 156 to the position shown in Figs. 7 and 11 thereby causing the cam surfaces 158 to move the locking plungers 159 into engagement with the upper feed drum 8 thereby connecting the latter to the driving gear 136. The operator then grasps the control handle 130 and swings the shipper member 99 to effect application of the slow speed clutch 109, 112. The feed drum is then driven at a slow speed from the motor through gearing 55, 56, 59, 63, 64, 68, 75, worm gearing 84, 86, spur gearing 92, 93, 135, and internal gear 136 and rotating the latter together with the upper feed drum 8 at a slow speed, winding in the cable 6, and sumping the cutter bar 4 beneath the face of the coal. After the cutter bar has been sumped beneath the coal face the operator moves the control member 156 to release the plungers 159 from the upper feed drum thereby moving the parts to the position shown in Figs. 15 and 16 with both drums released from the drive and the anchor or roof jack adjacent the face is knocked down and moved to a point adjacent the left hand rib and the feed cable 6 is then extended laterally from the front guide roll 190 to the anchor. The operator then rotates the control member 156 to the position shown in Fig. 12 thereby moving the lower plungers 163 within the recesses 166 in the bottom drum 9, connecting this drum to the drive. The fast speed controlling clutch 105, 108 within the fast speed gear 85 is then applied and the controlling cable 7 on the bottom

- drum 9 is then wound in at a high speed thereby straightening the machine up so that its longitudinal axis is substantially perpendicular to the coal face, the machine then being in the position shown in Fig. 1. The fast speed clutch is then released and the control member 156 moved to the position shown in Figs. 13 and 14 with the locking plungers 159, 163 moved into locking engagement with both drums. The slow speed clutch within the slow speed worm gear 86 is then applied and the drums 8 and 9 are rotated together winding in the feed cable 6 at a slow speed while the control cable 7 is slowly paid out and as a result the machine is fed laterally at a cutting speed relative to the coal face. If it is desired to angle the machine relative to the coal face, for instance, if a sulphur ball or some similar unduly hard substance is encountered by the cutter bar, the operator may release the upper feed drum 8 from its drive and connect the lower control drum 9 to the fast speed drive thereby causing the control cable 7 to be wound in drawing the rear end of the machine laterally toward the right hand rib and angling the machine relative to the face. The machine may be angled in the opposite direction by disconnecting the lower control drum 9 from its drive while rotation of the upper feed drum 8 continues thereby causing the rear end of the machine to be swung forwardly. After the transverse cutting operation is completed the machine is angled in a usual manner relative to the face. The feed cable 6 is then disconnected from its anchor and extended rearwardly of the machine to a suitable anchor and upon rotation of the feed drum 8 the cutter bar is withdrawn from the face. The machine is adapted to be hauled about the mine at a fast speed by means of the lower control drum 9 and its cooperating cable. It is obvious that the machine may cut from left to right by reversing the motor, rewinding the cables on their respective drums, and reversing the position of the cutter bits.
- As a result of this invention it will be noted that an improved mining machine of the flexibly fed continuous cutter room and pillar type is provided which is of an exceedingly low and compact construction especially adapted to use in mines having narrow or thin veins of coal. It will further be noted that an improved mining machine is provided having improved flexible feeding means comprising coaxial drums rotatable about a vertical axis and so arranged as to produce an exceedingly low machine while drums of comparatively large diameter are retained. It will still further be noted that by providing the improved controlling means within the drums it is possible to effect simultaneous or independent rotation of the drums. It will further be observed that during feed-

ing of the machine during the cutting operation the feed drum winds in its cooperating cable at a slow speed while the control cable is unwound or paid out at a corresponding speed and that upon application of the fast speed clutch the control cable 7 may be wound in at a relatively high speed. It will further be noted that the control means for the drums is exceedingly simple, a "one-dial control" being employed for controlling both drums thereby greatly simplifying and facilitating control of the machine. These and other advantages of the improved mining machine will, however, be clearly apparent to those skilled in this art.

While I have in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining machine, a horizontal motor having its power shaft extending longitudinally of the machine, cutting mechanism driven from one end of said motor, and feeding mechanism driven from the opposite end of said motor including coaxially arranged relatively rotatable feed operating and controlling members each adapted to cooperate with flexible feeding means, and plural speed driving gearing for driving said members at one speed in one direction and at a different speed in the opposite direction while said motor operates continuously in the same direction.

2. In a mining machine, a horizontal motor having its power shaft extending longitudinally of the machine, cutting mechanism driven from one end of said motor, and feeding mechanism driven from the opposite end of said motor including coaxially arranged relatively rotatable feed operating and controlling members disposed on a vertical axis and each adapted to cooperate with flexible feeding means, and plural speed driving gearing for driving said feed operating and controlling members either independently of the other.

3. In a mining machine, a horizontal motor having its power shaft extending longitudinally of the machine, cutting mechanism driven from one end of said motor, and feeding mechanism driven from the opposite end of said motor including coaxially arranged relatively rotatable feed operating and controlling members disposed on a vertical axis and each adapted to cooperate with flexible feeding means, and plural speed driving gearing for driving said feed operating and controlling members either independently of the other at a slow speed in one direction and at

- a relatively high speed in the opposite direction.
4. In a mining machine, a motor, and machine feeding mechanism driven thereby including coaxially arranged relatively rotatable feed operating and controlling members disposed on a vertical axis and each adapted to cooperate with flexible feeding means, and means for connecting said members both simultaneously or either independently of the other in driving relation with said motor.
5. In a mining machine, a machine frame slidable on its bottom on the mine bottom, a horizontal motor thereon having its power shaft horizontally disposed and extending longitudinally of said frame, cutting mechanism driven from one end of said motor and including a cutter bar projecting from said frame, and feeding means driven from the opposite end of said motor comprising coaxial relatively rotatable feed operating and controlling members each adapted to cooperate with flexible feeding means and disposed on a vertical axis, and means driven by said motor for driving either of said members independently of the other.
6. In a mining machine, a machine frame slidable on its bottom on the mine bottom, a horizontal motor thereon having its power shaft horizontally disposed and extending longitudinally of said frame, cutting mechanism driven from one end of said motor and including a cutter bar projecting from said frame, and feeding means driven from the opposite end of said motor comprising coaxial relatively rotatable feed operating and controlling members each adapted to cooperate with flexible feeding means and disposed on a vertical axis, and means driven by said motor for driving said members both simultaneously or either independently of the other.
7. In a mining machine, a machine frame slidable on its bottom on the mine bottom, a motor, cutting mechanism driven by said motor and including a cutter bar projecting from said frame, and feeding means driven by said motor comprising coaxial relatively rotatable feed operating and controlling members each adapted to cooperate with flexible feeding means and disposed on a vertical axis at the end of the machine remote from said bar, and means driven by said motor for driving either of said members independently of the other.
8. In a mining machine, a machine frame slidable on its bottom on the mine bottom, a motor, cutting mechanism driven by said motor and including a cutter bar projecting from said frame, and feeding means driven by said motor comprising coaxial relatively rotatable feed operating and controlling members each adapted to cooperate with flexible feeding means and disposed on a vertical axis at the end of the machine remote from said bar, and means driven by said motor for
- driving said members both simultaneously or either independently of the other.
9. In a mining machine, a motor, and machine feeding means driven thereby including coaxial relatively rotatable feed operating and controlling members arranged in substantially end abutting relation with their axes parallel to a transverse vertical plane and each adapted to cooperate with flexible feeding means, a driving member, and clutch mechanism for connecting said feed operating and controlling members both simultaneously or either independently of the other to said driving member.
10. In a mining machine, a motor, and machine feeding means driven thereby comprising coaxial feed and control drums, a driving member arranged coaxially with and disposed within said drums, relatively movable plungers carried by said driving member, and common control means for actuating said plungers to independently connect said drums to said driving member.
11. In a mining machine, a motor, and machine feeding means driven thereby comprising coaxial feed and control drums, a driving member arranged coaxially with and disposed within said drums, relatively movable plungers carried by said driving member, and common control means for actuating said plungers to simultaneously or independently connect said drums to said driving member.
12. In a mining machine, a motor, and machine feeding means driven thereby comprising coaxial relatively rotatable winding drums, a drum driver member arranged coaxially with and disposed within said drums, and common control means carried by said driver member for independently or simultaneously connecting said drums directly thereto for rotation therewith.
13. In a mining machine, a motor, and machine feeding means driven thereby comprising coaxial relatively rotatable winding drums, a drum driver member arranged coaxially with and disposed within said drums, elements carried by said driver member and engageable with said drums for independently connecting the latter to said driver member for rotation therewith, and rotatable means engaging said elements for actuating the same.
14. In a mining machine, a machine frame adapted to rest upon and slide in any direction over the mine bottom, a motor carried by said frame, cutting mechanism driven by said motor including a kerf cutter projecting from said frame, and feeding means driven by said motor including relatively rotatable feed operating and controlling members each rotating on a vertical axis and adapted to cooperate directly with flexible feeding means and motor operated driving and controlling mechanism for said members for effecting rotation of one of said mem- 120 125 130

- bers in a direction to draw in its respective flexible feeding means at a relatively slow speed and for rotating said other member in a direction to pay out its respective flexible feeding means at a similar speed, means whereby rotation of one of said members may be effected at a speed slower than said other member, and mechanism driven by said motor for effecting rotation of said paying-out member in a direction to draw in its respective flexible feeding means without reversing said motor or changing the relation of said flexible means with respect thereto.
15. In a mining machine, a machine frame adapted to rest upon and slide in any direction over the mine bottom, a motor carried by said frame, cutting mechanism driven by said motor including a kerf cutter projecting from said frame, and feeding means driven by said motor including coaxially arranged relatively rotatable feed operating and controlling members rotating on a vertical axis and adapted to cooperate directly with flexible feeding means and driving and controlling mechanism for said members for effecting rotation of one of said members in a direction to draw in its respective flexible feeding means at a relatively slow speed and for rotating said other member in a direction to pay out its respective flexible feeding means at a similar speed, means whereby rotation of one of said members may be effected at a speed slower than said other member, and mechanism driven by said motor for effecting rotation of said paying-out member in a direction to draw in its respective flexible feeding means.
16. In a mining machine, a machine frame adapted to rest upon and slide in any direction over the mine bottom, a motor carried by said frame, cutting mechanism driven by said motor including a kerf cutter projecting from said frame, and feeding means driven by said motor including relatively rotatable coaxially arranged feed operating and controlling members rotating on a vertical axis and each adapted to cooperate directly with flexible feeding means and driving and controlling mechanism for effecting rotation of said members simultaneously at either a relatively high speed or a relatively low speed and mechanism operable at will for disconnecting either member from its drive while the other member is driven.
17. In a mining machine, a machine frame adapted to rest upon and slide in any direction over the mine bottom, a motor carried by said frame, cutting mechanism driven by said motor including a kerf cutter projecting from said frame, and feeding means for the machine including a plurality of relatively rotatable coaxially arranged feed operating and controlling members rotatable on a vertical axis and each adapted to cooperate directly with flexible feeding means, and driving and controlling means for said members for rotating the same either separately or both simultaneously at either a relatively high speed or at a relatively low speed and including fast and slow speed worm gear trains selectively operative to drive said members at fast and slow predetermined speeds, said gear trains each including a worm wheel rotating about a vertical axis.
18. In a mining machine, a machine frame adapted to rest upon and slide in any direction over the mine bottom, a motor carried by said frame, cutting mechanism driven by said motor including a kerf cutter projecting from said frame, and feeding means for the machine including a plurality of relatively rotatable feed operating and controlling members each adapted to cooperate directly with flexible feeding means, and driving and controlling means for said members for rotating the same either separately or both simultaneously at either a relatively high speed or at a relatively low speed and including fast and slow speed transmission means for said members including coaxial fast and slow speed terminal gears arranged with their axes vertical and friction clutches coaxial with said gears, one individual to each gear, for selectively connecting said gears in driving relation with said members.
19. In a mining machine, a machine frame adapted to rest upon and slide in any direction over the mine bottom, a motor carried by said frame, cutting mechanism driven by said motor including a kerf cutter projecting from said frame, and feeding means for the machine including a plurality of relatively rotatable feed operating and controlling members each adapted to cooperate directly with flexible feeding means, and driving and controlling means for said members for rotating the same either separately or both simultaneously at either a relatively high speed or at a relatively low speed and including fast and slow speed worm gear trains selectively operative to drive said members at fast and slow predetermined speeds, said gear trains each including a worm wheel rotating about a vertical axis.
20. In a mining machine, a machine frame adapted to rest upon and slide in any direction over the mine bottom, a motor carried by said frame, cutting mechanism driven by said motor including a kerf cutter projecting from said frame, and feeding means for the machine including a plurality of relatively rotatable feed operating and controlling members each adapted to cooperate directly with flexible feeding means, and driving and controlling means for said members for rotating the same either separately or both simultaneously at either a relatively high speed or at a relatively low speed and including fast and slow speed worm gear trains selectively operative to drive said members at fast and slow predetermined speeds, said gear trains each including a worm wheel rotating about a vertical axis and friction clutches for selectively connect-

ing said worm gear trains in driving relation with said members.

21. In a mining machine, a machine frame adapted to rest upon and slide in any direction over the mine bottom, a motor carried by said frame, cutting mechanism driven by said motor including a kerf cutter projecting from said frame at one end thereof, and feeding means driven by said motor including coaxially arranged relatively rotatable feed operating and controlling members disposed on a vertical axis at the end of said frame remote from the end thereof from which the kerf cutter projects and each adapted to cooperate with flexible feeding means, and driving and controlling means for said members for driving said members either independently or both simultaneously at either a relatively fast or a relatively slow speed.

22. In a mining machine, a machine frame adapted to rest upon and slide in any direction over the mine bottom, a motor carried by said frame, cutting mechanism driven by said motor including a kerf cutter projecting from said frame, and feeding means driven by said motor including coaxially arranged relatively rotatable feed operating and controlling members disposed on a vertical axis and each adapted to cooperate with flexible feeding means and driving and controlling means for said members for independently or simultaneously driving said members at either a relatively fast speed or a relatively slow speed including a rotatable driving member coaxial with said members, clutch devices carried by said driving member, and means for actuating said clutch devices to connect either or both of said feed operating and controlling members to said driving member.

23. In a mining machine, a machine frame adapted to rest upon and slide in any direction over the mine bottom, a motor carried by said frame, cutting mechanism driven by said motor including a kerf cutter projecting from said frame, and feeding means driven by said motor including coaxially arranged relatively rotatable feed operating and controlling members disposed on a vertical axis and each adapted to cooperate with flexible feeding means and driving and controlling means for said members for independently or simultaneously driving said members at either a relatively fast speed or a relatively slow speed including a rotatable driving member disposed within said members, a gear secured to said driving member, a pinion meshing with said gear, a hollow transmission shaft driving said pinion, clutch devices carried by said driving member, and means including an operating element extending through said hollow shaft and said pinion for actuating said clutch devices to connect either or both of said feed operating

and controlling members to said driving member.

24. In a mining machine, a machine frame adapted to rest upon and slide in any direction over the mine bottom, a motor carried by said frame, cutting mechanism driven by said motor including a kerf cutter projecting from said frame, and feeding means driven by said motor including coaxially arranged relatively rotatable feed operating and controlling members disposed on a vertical axis and each adapted to cooperate with flexible feeding means and driving and controlling means for said members for independently or simultaneously driving said members at either a relatively fast speed or a relatively slow speed including a rotatable driving member coaxial with said members, clutch devices carried by said driving member for connecting either or both of said feed operating and controlling members thereto and including clutch elements shiftable into engagement with either member, and a rotatable cam device for shifting said clutch devices.

25. In a mining machine, a machine frame adapted to rest upon and slide in any direction over the mine bottom, a motor carried by said frame, cutting mechanism driven by said motor including a kerf cutter projecting from said frame, and feeding means driven by said motor including relatively rotatable coaxially arranged feed operating and controlling members disposed on a vertical axis and each adapted to cooperate with flexible feeding means, and driving and controlling means for said members including clutch devices, operable at will, for connecting either or both of said members in driving relation with said motor.

26. In a mining machine, a machine frame adapted to rest upon and slide in any direction over the mine bottom, a motor carried by said frame, cutting mechanism driven by said motor including a kerf cutter projecting from said frame, and feeding means driven by said motor including relatively rotatable coaxially arranged feed operating and controlling members disposed on a vertical axis and each adapted to cooperate with flexible feeding means, and driving and controlling means for said members including frictionally controlled fast and slow speed transmission means and clutch devices, operable at will, for connecting either or both of said members in driving relation with said transmission means.

27. In a mining machine, feeding mechanism including relatively rotatable feed operating and controlling drums arranged in substantially end abutting relation each adapted to cooperate with a flexible feed cable, and mechanism for separately or simultaneously driving said drums including a rotatable driver member disposed within said drums and on which said drums are rotatably

supported, and clutch devices for connecting either or both drums to said member.

28. In a mining machine, feeding mechanism including relatively rotatable feed operating and controlling drums each adapted to cooperate with a flexible feed cable, and mechanism for separately or simultaneously driving said drums including a rotatable driver member disposed within said drums 5 and clutch devices for connecting either or both drums to said member and including slideable plungers carried by said driver member, and cam means for actuating said plungers.

10 29. In a mining machine, feeding mechanism including relatively rotatable feed operating and controlling drums each adapted to cooperate with a flexible feed cable, and mechanism for separately or simultaneously 20 driving said drums including a rotatable driver member disposed within said drums and clutch devices for connecting either or both drums to said member and including sliding discs engageable with sockets in said 25 drums, and rotatable cam means for sliding said discs into engagement with said sockets and having sockets for receiving said discs.

30. In a mining machine, feeding means including relatively rotatable feed operating 30 and controlling drums each adapted to cooperate with a flexible feed cable, and mechanism for separately or simultaneously driving said drums including a rotatable driver member arranged coaxially with said drums, 35 means for rotating said member including a hollow transmission shaft, clutch devices carried by said member for connecting either or both of said drums thereto, and actuating means for said clutch devices including an operating element extending through said 40 hollow shaft.

31. In a mining machine, feeding means including relatively rotatable feed operating and controlling drums each adapted to cooperate with a flexible feed cable, and mechanism for separately or simultaneously driving said drums including a rotatable driver member arranged coaxially with said drums, 45 means for rotating said member including a hollow transmission shaft, clutch devices carried by said member for connecting either or both of said drums thereto, and actuating means for said clutch devices including a rotatable operating member disposed on an axis 50 coaxial with said driver member and rotating means for said clutch operating member including an operating element extending through said hollow shaft.

55 32. In a mining machine, the combination 60 with a frame adapted to rest upon and slide in any direction over the mine bottom, a horizontal motor having its power shaft extending longitudinally of the machine, and cutting mechanism driven from one end of said motor, of feeding and guiding mecha-

nism driven from the opposite end of said motor and including coaxially arranged relatively rotatable feeding members arranged in substantially end abutting relation and disposed on axes lying in a vertical transverse 70 plane and each adapted to cooperate directly with flexible feeding means, and means for separately or simultaneously connecting said members in driving relation with said motor.

75 33. In a mining machine, the combination with a frame adapted to rest upon and slide in any direction over the mine bottom, a horizontal motor having its power shaft extending longitudinally of the machine, and cutting mechanism driven from one end of said 80 motor, of feeding and guiding mechanism driven from the opposite end of said motor and including coaxially arranged relatively rotatable feeding members disposed on a vertical axis and each adapted to cooperate directly with flexible feeding means, and means for separately or simultaneously connecting said members in driving relation with said motor.

85 34. In a mining machine, the combination with a frame adapted to rest upon and slide in any direction over the mine bottom, a horizontal motor having its power shaft extending longitudinally of the machine, and cutting mechanism driven from one end of said 90 motor, of feeding and guiding mechanism driven from the opposite end of said motor and including coaxially arranged relatively rotatable feeding members arranged in substantially end abutting relation and disposed 95 on axes lying in a vertical transverse plane and each adapted to cooperate directly with flexible feeding means, and plural speed driving gearing between said motor and said members for driving said members either 100 separately or simultaneously at relatively 105 high speed or at relatively low speed.

110 35. In a mining machine, the combination with a frame adapted to rest upon and slide in any direction over the mine bottom, a horizontal motor having its power shaft extending longitudinally of the machine, and cutting mechanism driven from one end of said 115 motor, of feeding and guiding mechanism driven from the opposite end of said motor and including coaxially arranged relatively rotatable feeding members disposed on a vertical axis and each adapted to cooperate directly with flexible feeding means, and plural speed driving gearing between said 120 motor and said members for driving said members either separately or simultaneously at relatively high speed or at relatively low speed.

125 36. In a mining machine, the combination with a frame adapted to rest upon and slide in any direction over the mine bottom, a horizontal motor having its power shaft extending longitudinally of the machine, and cutting mechanism driven from one end of said 130

motor, of feeding and guiding mechanism driven from the opposite end of said motor and including coaxially arranged relatively rotatable feeding members disposed on axes 5 lying in a vertical transverse plane and each adapted to cooperate directly with flexible feeding means, and plural speed driving gearing between said motor and said members for driving either of said members separately or both simultaneously at a relatively low speed in one direction and at a relatively high speed in the opposite direction while said motor runs continuously in the same direction.

15 37. In a mining machine, the combination with a machine frame slideable on its bottom on the mine bottom, a horizontal motor thereon having its power shaft horizontally disposed and extending longitudinally of said 20 frame and cutting mechanism driven from one end of said motor and including a cutter bar projecting from said frame, of feeding means driven from the opposite end of said motor comprising coaxial relatively rotatable 25 feed operating and controlling members arranged in substantially end abutting relation and disposed on axes lying in a transverse vertical plane and each adapted to cooperate with flexible feeding means and disposed at 30 the end of the machine remote from said bar, and means driven by said motor for independently driving said members.

38. In a mining machine, the combination with a machine frame slideable on its bottom 35 on the mine bottom, a horizontal motor thereon having its power shaft horizontally disposed and extending longitudinally of said frame and cutting mechanism driven from one end of said motor and including a cutter 40 bar projecting from said frame, of feeding means driven from the opposite end of said motor comprising coaxial relatively rotatable feed operating and controlling members arranged in substantially end abutting relation 45 and disposed on axes lying in a transverse vertical plane and each adapted to cooperate with flexible feeding means and disposed at the end of the machine remote from said bar, and means driven by said motor for simultaneously or independently driving said members.

39. In a mining machine, the combination with a frame adapted to rest upon and slide in any direction over the mine bottom and cutting mechanism mounted thereon including a 55 forwardly projecting cutter bar, a cutter driving sprocket at the forward end of said frame and a motor arranged centrally on said frame for driving said sprocket; of feeding and guiding mechanism driven by said motor comprising two flexible feeding and guiding elements adapted to cooperate with external extraneous abutments, two 60 winding drums mounted for rotation on said frame at the rear end thereof remote from

said cutting mechanism and with which said flexible elements respectively cooperate, and power actuated means controllable at will to cause rotation of said drums both simultaneously or either separately from the other at a 70 relatively high speed in one direction and at a relatively low speed in the opposite direction without reversing said motor.

40. In a mining machine, the combination with a frame adapted to rest upon and slide 75 in any direction over the mine bottom and cutting mechanism mounted thereon, of feeding and guiding mechanism comprising two flexible feeding and guiding elements adapted to cooperate with external extraneous abutments, two winding drums mounted for rotation on said frame about aligned vertical axes and with which said flexible elements respectively cooperate, and power actuated means 80 controllable at will to cause rotation of said drums both simultaneously or either separately from the other at either of two speeds.

41. In a mining machine, the combination with a frame adapted to rest upon and slide 85 in any direction over the mine bottom and cutting mechanism mounted thereon, of feeding and guiding mechanism comprising two flexible feeding and guiding elements adapted to cooperate with external extraneous abutments, two winding drums mounted for rotation on said frame about vertical axes and with which said flexible elements respectively cooperate, and optionally controlled power actuated means to cause rotation of 90 said drums both simultaneously or either separately from the other at either of two speeds and including a plural speed transmission mechanism having slow speed driving means and fast speed driving means and frictionally controlled means, one individual to each of said fast and slow speed means, for effecting selectively drive through said fast and slow speed means.

42. In a mining machine, the combination with a frame adapted to rest upon and slide 100 in any direction over the mine bottom and cutting mechanism mounted thereon including a forwardly projecting cutter bar and a cutter driving sprocket at the forward end of said frame, of feeding and guiding mechanism comprising two flexible feeding and guiding elements adapted to cooperate with external extraneous abutments, two winding drums mounted for rotation on said frame about aligned axes and with which said flexible elements respectively cooperate, said drums being arranged on said frame at the end thereof remote from said cutter driving sprocket, and optionally controlled power 105 actuated means to cause rotation of said drums both simultaneously or either separately from the other at either of two speeds and including a plural speed transmission mechanism having slow speed driving means and fast speed driving means and frictional 110

115 43. In a mining machine, the combination with a frame adapted to rest upon and slide in any direction over the mine bottom and cutting mechanism mounted thereon including a forwardly projecting cutter bar, a cutter driving sprocket at the forward end of said frame and a motor arranged centrally on said frame for driving said sprocket; of feeding and guiding mechanism driven by said motor comprising two flexible feeding and guiding elements adapted to cooperate with external extraneous abutments, two winding drums mounted for rotation on said frame at the rear end thereof remote from

120 44. In a mining machine, the combination with a frame adapted to rest upon and slide in any direction over the mine bottom and cutting mechanism mounted thereon including a forwardly projecting cutter bar, a cutter driving sprocket at the forward end of said frame and a motor arranged centrally on said frame for driving said sprocket; of feeding and guiding mechanism driven by said motor comprising two flexible feeding and guiding elements adapted to cooperate with external extraneous abutments, two winding drums mounted for rotation on said frame at the rear end thereof remote from

125 45. In a mining machine, the combination with a frame adapted to rest upon and slide in any direction over the mine bottom and cutting mechanism mounted thereon including a forwardly projecting cutter bar, a cutter driving sprocket at the forward end of said frame and a motor arranged centrally on said frame for driving said sprocket; of feeding and guiding mechanism driven by said motor comprising two flexible feeding and guiding elements adapted to cooperate with external extraneous abutments, two winding drums mounted for rotation on said frame at the rear end thereof remote from

130 46. In a mining machine, the combination with a frame adapted to rest upon and slide in any direction over the mine bottom and cutting mechanism mounted thereon including a forwardly projecting cutter bar, a cutter driving sprocket at the forward end of said frame and a motor arranged centrally on said frame for driving said sprocket; of feeding and guiding mechanism driven by said motor comprising two flexible feeding and guiding elements adapted to cooperate with external extraneous abutments, two winding drums mounted for rotation on said frame at the rear end thereof remote from

ly controlled means, one individual to each of said fast and slow speed means, for effecting selectively drive through said fast and slow speed means.

43. In a mining machine, the combination with a frame adapted to rest upon and slide in any direction over the mine bottom and cutting mechanism mounted thereon, of feeding and guiding mechanism comprising two flexible feeding and guiding elements adapted to cooperate with external extraneous abutments, two winding drums mounted for rotation on said frame about alined vertical axes and with which said flexible elements respectively cooperate, and optionally controlled power actuated means to cause rotation of said drums both simultaneously or either separately from the other at either of two speeds and including a plural speed transmission mechanism having slow speed driving means and fast speed driving means and frictionally controlled means, one individual to each of said fast and slow speed means, for effecting selectively drive through said fast and slow speed means.
44. In a mining machine, the combination with a frame adapted to rest upon and slide in any direction over the mine bottom and cutting mechanism mounted thereon including a forwardly projecting cutter bar and a cutter driving sprocket at the forward end of said frame, of feeding and guiding mechanism comprising two flexible feeding and guiding elements adapted to cooperate with external extraneous abutments, two coaxial winding drums mounted for rotation on said frame at the end thereof remote from said cutter driving sprocket and with which said flexible elements respectively cooperate, and optionally controlled power actuated means to cause rotation of said drums both simultaneously or either separately from the other at either of two predetermined speeds and including a fast speed gear train and a slow speed gear train, and frictional devices for selectively rendering said gear trains effective.
45. In a mining machine, the combination with a frame adapted to rest upon and slide in any direction over the mine bottom and cutting mechanism mounted thereon including a forwardly projecting cutter bar and a cutter driving sprocket at the forward end of said frame, of feeding and guiding mechanism comprising two flexible feeding and guiding elements adapted to cooperate with external extraneous abutments, two coaxial winding drums mounted for rotation on said frame at the end thereof remote from said cutter driving sprocket and with which said flexible elements respectively cooperate, and optionally controlled power actuated means to cause rotation of said drums both simultaneously or either separately from the other at either of two speeds and including

a fast speed gear train and a slow speed gear train and manually controllable friction clutches, one individual to each gear train, for selectively rendering said gear trains effective.

46. In a mining machine, the combination with a frame adapted to rest upon and slide in any direction over the mine bottom and cutting mechanism mounted thereon including a forwardly projecting cutter bar and a cutter driving sprocket at the forward end of said frame, of feeding and guiding mechanism comprising two flexible feeding and guiding elements adapted to cooperate with external extraneous abutments, two winding drums mounted for rotation on said frame about alined axes and with which said flexible elements respectively cooperate, said drums being arranged on said frame at the end thereof remote from said cutter driving sprocket, and optionally controlled power actuated means to cause rotation of said drums both simultaneously or either separately from the other at either of two speeds and including a fast speed gear train and a slow speed gear train and manually controllable friction clutches, one individual to each gear train, for selectively rendering said gear trains effective.

47. In a mining machine, the combination with a frame adapted to rest upon and slide in any direction over the mine bottom and cutting mechanism mounted thereon, of feeding and guiding mechanism comprising two flexible feeding and guiding elements adapted to cooperate with external extraneous abutments, two winding drums mounted for rotation on said frame about vertical axes and with which said flexible elements respectively cooperate, and optionally controlled power actuated means to cause rotation of said drums both simultaneously or either separately from the other at either of two speeds and including a fast speed gear train and a slow speed gear train and manually controllable friction clutches, one individual to each gear train, for selectively rendering said gear trains effective.

48. In a mining machine, the combination with a frame adapted to rest upon and slide in any direction over the mine bottom and cutting mechanism mounted thereon, of feeding and guiding mechanism comprising two flexible feeding and guiding elements adapted to cooperate with external extraneous abutments, two winding drums mounted for rotation on said frame about alined vertical axes and with which said flexible elements respectively cooperate, and optionally controlled power actuated means to cause rotation of said drums both simultaneously or either separately from the other at either of two speeds and including a fast speed gear train and a slow speed gear train and manually controllable friction clutches, one individual to each gear train, for selectively rendering said gear trains effective.

vidual to each gear train, for selectively rendering said gear trains effective.

49. A mining machine feeding mechanism comprising relatively rotatable feeding members each adapted to cooperate with flexible feeding means, and motor driven transmission mechanism for driving either of said members separately or both simultaneously at relatively high speed or at relatively low speed including a plural predetermined speed transmission mechanism having a fast speed terminal element and a slow speed terminal element, said elements being coaxially arranged and disposed on a vertical axis, and frictional controlling means for selectively effecting drive through said terminal elements.

50. A mining machine feeding mechanism comprising relatively rotatable feeding members each adapted to cooperate with flexible feeding means, and motor driven transmission mechanism for driving either of said members separately or both simultaneously at relatively high speed or at relatively low speed including a plural predetermined speed transmission mechanism having a fast speed terminal element and a slow speed terminal element, said elements being coaxially arranged and disposed on axes parallel with the axes of said feeding members, and frictional controlling means for selectively effecting drive through said terminal elements.

51. A mining machine feeding mechanism comprising relatively rotatable feeding members disposed on vertical axes and each adapted to cooperate directly with flexible feeding means, motor operated devices for effecting rotation of either of said members separately or both simultaneously at relatively high speed or at relatively low speed and including a terminal driving element, and devices operable at will for disconnecting said feeding members from the terminal driving element of said motor operated devices to permit free rotation of said members.

52. A mining machine feeding mechanism comprising relatively rotatable feeding members disposed on aligned vertical axes and each adapted to cooperate directly with flexible feeding means, motor operated devices for effecting rotation of either of said members separately or both simultaneously at relatively high speed or at relatively low speed, and devices operable at will for disconnecting said feeding members from said motor operated devices to permit free rotation of said members.

53. In a mining machine feeding mechanism, relatively rotatable feeding members arranged in coaxial relation and each adapted to cooperate directly with flexible feeding means, and motor operated devices for rotating either of said members separately or both simultaneously including a driving element arranged within said feeding members, and

clutch devices carried by said driving element for connecting either or both of said feeding members to said driving element.

54. In a mining machine feeding mechanism, relatively rotatable feeding members arranged in coaxial relation and each adapted to cooperate directly with flexible feeding means, and motor operated devices for rotating either of said members separately or both simultaneously including a driving element arranged within said feeding members and on which one of the same is journaled, and clutch devices including shiftable clutch elements mounted directly on and rotatable bodily with said driving element for connecting either or both of said feeding members to said driving element.

55. In a mining machine feeding mechanism, relatively rotatable feeding members disposed in coaxial relation and each adapted to cooperate directly with flexible feeding means, and motor operated devices for rotating either of said members separately or both simultaneously including a driving member arranged coaxially with said feeding members, and clutch devices carried by said driving member for connecting either or both of said feeding members to said driving member.

56. In a mining machine feeding mechanism, relatively rotatable feeding members arranged in coaxial relation and each adapted to cooperate directly with flexible feeding means, and motor operated devices for rotating either of said members separately or both simultaneously including a cylindrical driving member disposed within said members and on which the latter are journaled, and clutch devices including shiftable clutch elements mounted directly on and rotatable bodily with said cylindrical driving member for connecting either or both of said feeding members to said driving member or to permit rotation of said feeding members relative to said driving member.

57. In a mining machine feeding mechanism, relatively rotatable feeding members disposed in coaxial relation and each adapted to cooperate with flexible feeding means, and motor operated devices for rotating either of said members separately or both simultaneously including a cylindrical driving member mounted for rotation within said feeding members and on which the latter are journaled, and clutch devices operable at will during rotation of said driving member including shiftable clutch elements mounted directly on and rotatable bodily with said cylindrical driving member for connecting either or both of said feeding members to said driving member.

58. In a mining machine feeding mechanism, relatively rotatable feeding members disposed in coaxial relation and each adapt-

- ed to cooperate with flexible feeding means, and motor operated devices for rotating either of said members separately or both simultaneously including a cylindrical driving member mounted for rotation within said feeding members and on which the latter are journaled, and clutch devices operable at will during rotation of said driving member for connecting either or both of said feeding members to said driving member for rotation therewith or to permit rotation of said feeding members relative to said driving member, and including a controlling element mounted for rotation about the axis of said driving member.
59. In a mining machine, a motor, and machine feeding mechanism driven thereby including coaxially arranged relatively rotatable feed operating and controlling members disposed on a vertical axis and each adapted to cooperate with flexible feed means, and means for connecting said members either independently of the other in driving relation with said motor.
60. In a mining machine, a motor, and machine feeding means driven thereby including coaxial relatively rotatable feed operating and controlling members arranged in substantially end abutting relation with their axes parallel to a transverse vertical plane and each adapted to cooperate with flexible feeding means, a driving member, and clutch mechanism for connecting said feed operating and controlling members either independently of the other to said driving member.
61. In a mining machine, a machine frame adapted to rest upon and slide in any direction over the mine bottom, a motor carried by said frame, cutting mechanism driven by said motor including a kerf cutter projecting from said frame, and feeding means driven by said motor including coaxially arranged relatively rotatable feed operating and controlling members disposed on a vertical axis and each adapted to cooperate with flexible feeding means and driving and controlling means for said members for driving said members either independently of the other at either a relatively fast speed or a relatively slow speed including a rotatable driving member coaxial with said members, clutch devices carried by said driving member, and means for actuating said clutch devices to connect either or both of said feed operating and controlling members to said driving member.
62. In a mining machine, a machine frame adapted to rest upon and slide in any direction over the mine bottom, a motor carried by said frame, cutting mechanism driven by said motor including a kerf cutter projecting from said frame, and feeding means driven by said motor including coaxially arranged relatively rotatable feed operating and controlling members disposed on a vertical axis and each adapted to cooperate with flexible feeding means and driving and controlling means for said members for driving said members either independently of the other at either a relatively fast speed or a relatively slow speed including a rotatable driving member coaxial with said members, clutch devices carried by said driving member, and means for actuating said clutch devices to connect either or both of said feed operating and controlling members to said driving member.
63. In a mining machine, a machine frame adapted to rest upon and slide in any direction over the mine bottom, a motor carried by said frame, cutting mechanism driven by said motor including a kerf cutter projecting from said frame, and feeding means driven by said motor including coaxially arranged relatively rotatable feed operating and controlling members disposed on a vertical axis and each adapted to cooperate with flexible feeding means and driving and controlling means for said members for driving said members either independently of the other at either a relatively fast speed or a relatively slow speed including a rotatable driving member coaxial with said members, clutch devices carried by said driving member for connecting either or both of said feed operating and controlling members thereto and including clutch elements shiftable into engagement with either member, and a rotatable cam device for shifting said clutch devices.
64. In a mining machine, feeding mechanism including relatively rotatable feed operating and controlling drums each adapted to cooperate with a flexible feed cable, and mechanism for driving said drums either independently of the other including a rotatable driver member disposed within said drums and clutch devices for connecting either or both drums to said member and including slidable plungers carried by said driver member, and cam means for actuating said plungers.
65. In a mining machine, feeding mechanism including relatively rotatable feed operating and controlling drums each adapted to cooperate with a flexible feed cable, and mechanism for driving said drums either independently of the other including a rotatable driver member disposed within said drums and clutch devices for connecting either or both drums to said member and including sliding discs engageable with sockets in said drums, and rotatable cam means for sliding said discs into engagement with said

sockets and having sockets for receiving said discs.

66. In a mining machine, feeding means including relatively rotatable feed operating and controlling drums each adapted to cooperate with a flexible feed cable, and mechanism for driving said drums either independently of the other including a rotatable driver member arranged coaxially with said drums, means for rotating said member including a hollow transmission shaft, clutch devices carried by said member for connecting either or both of said drums thereto, and actuating means for said clutch devices including an operating element extending through said hollow shaft.

67. In a mining machine, feeding means including relatively rotatable feed operating and controlling drums each adapted to cooperate with a flexible feed cable, and mechanism driving said drums either independently of the other including a rotatable driver member arranged coaxially with said drums, means for rotating said member including a hollow transmission shaft, clutch devices carried by said member for connecting either or both of said drums thereto, and actuating means for said clutch devices including a rotatable operating member disposed on an axis coaxial with said driver member and rotating means for said clutch operating member including an operating element extending through said hollow shaft.

68. In a mining machine feeding mechanism, relatively rotatable feeding members arranged in coaxial relation and each adapted to cooperate directly with flexible feeding means, and motor operated devices for rotating said members either independently of the other including a driving element arranged within said feeding members and on which one of the same is journaled, and clutch devices including shiftable clutch elements mounted directly on and rotatable bodily with said driving element for connecting either or both of said feeding members to said driving element.

69. In a mining machine feeding mechanism, relatively rotatable feeding members disposed in coaxial relation and each adapted to cooperate directly with flexible feeding means, and motor operated devices for rotating said members either independently of the other including a driving member arranged coaxially with said feeding members, and clutch devices carried by said driving member for connecting either or both of said feeding members to said driving member.

70. In testimony whereof I affix my signature.
MORRIS P. HOLMES.
